UNITED STATES PATENT OFFICE

103,176

DESIGN FOR A BUCKLE

Floyd A. Knoll, Buffalo, N. Y., assignor to Condor Products, Inc., Buffalo, N. Y.

Application November 3, 1936, Serial No. 65,680

Term of patent 14 years

To all whom it may concern:

Be it known that I, Floyd A. Knoll, a citizen of the United States, residing at Buffalo, Erie County, State of New York, have invented a new, original, and ornamental Design for Buckles, of which the following is a specification, reference being had to the accompanying drawing, forming a part thereof.

In said drawing:

Fig. 1 is a perspective view of a buckle showing my new design.

Fig. 2 is an end view thereof.

I claim:

The ornamental design for a buckle, as shown.

FLOYD A. KNOLL.
